V. L. CAPWELL
RAZOR STROPPING DEVICE

Filed May 19, 1924

V.L. Capwell Inventor

Ch. Parker
Attorney

UNITED STATES PATENT OFFICE.

VERNON L. CAPWELL, OF CLINTON, INDIANA.

RAZOR-STROPPING DEVICE.

Application filed May 19, 1924. Serial No. 714,475.

This invention relates to stropping devices and more particularly to a device adapted for stropping double edged safety razor blades.

5 An important object of the invention is to provide a device of the above mentioned character having a movable strop adapted to be moved in one direction to strop one side of each edge of the blade and to be 10 moved in the opposite direction to strop the other sides of the edges.

A further object of the invention is to provide automatic means for moving the edges of the blade away from the sides of 15 the strop when the latter is about to be reversed.

20 A further object of the invention is to provide means tending to urge the blade to a neutral position between the sides of the strop when no force is being applied to the strop, means being provided to afford protection for the edges of the blade to prevent 25 accidental contact with the strop.

A further object of the invention is to 30 provide a novel housing construction for the stropping device and a novel blade holding means.

35 A further object is to provide means for imparting motion to the blade carrier as the strop is moved to bring the edges of the blade firmly into contact with the stropping surfaces.

Other objects and advantages of the invention will be apparent during the course 40 of the following description.

In the drawings I have shown one embodiment of the invention. In this showing,

Figure 1 is a vertical transverse sectional view through the device,

Figure 2 is a vertical longitudinal sectional view parts being shown in elevation,

Figure 3 is an edge view of the stropping device,

Figure 4 is a similar view of the opposite edge,

Figure 5 is a perspective view of one of the casing sections,

Figure 6 is a similar view of the other casing section,

Figure 7 is a detailed perspective of the blade carrier in open position, and,

Figure 8 is an enlarged transverse sectional view through the blade carrier and associated elements.

Referring to the drawings, the numerals 10 and 11 designate substantially U-shaped casing sections preferably formed of stamped sheet metal. The casing section 10 is provided with a side portion 12 and end portions 13 while the casing section 11 is provided with a similar side portion 14 and ends 15. The ends 15 are preferably spaced apart a slightly greater distance than the ends 13 to receive the latter therebetween 60 to provide a casing having open upper and lower ends. The ends 13 and 15 are provided with upper aligned slots 16 having arcuate inner ends so that the inner ends form together a circular opening when the 65 casing is assembled. The ends 13 and 15 are similarly provided near their lower ends with openings 17 and 18. These openings or slots are shaped similar to the slots 16 to form circular openings when the casing 70 is assembled, the openings 18 being slightly larger than the openings 17. The casing sections are provided adjacent the openings 75 18 with narrow vertical slots 19 extending above and below the openings 18 for a purpose to be described. The casing sections are secured together by upper and lower rods 20 and a substantially central rod 21 as clearly shown in Figures 1 and 2.

The numeral 22 designates a roller or 80 shaft having reduced ends 23 arranged in the openings 16. The openings 16 form bearings for the reduced portions of the shaft 22 to permit the latter to freely operate. The shaft 22 is provided at one end 85 90 preferably outwardly of the casing with a disk 24 as shown in Figures 1 and 3 and this disk is provided with a pin 25 pivotally receiving one end of a link 26.

The numeral 27 designates a lower shaft 95 journaled in the openings 17 and 18, the shaft being provided with a reduced portion 28 arranged in the openings 17. The opposite end of the shaft is arranged within the openings 18 and has its outer end 100 preferably flush with the outer face of the end 15 as shown in Figure 2. The shaft is provided at the opposite end with a disk 29 having a pin 30 therein pivotally connected with the lower end of the link 26. 105 As shown in Figure 3 the pins 25 and 30 are oppositely arranged and it will be apparent that oscillating movement of the shaft 22 will cause simultaneous oscillation of the shaft 27 in an opposite direction. 110

tion. The shaft 27 is provided with an axial opening 31 extending throughout the greater portion of its length for a purpose to be described.

5 Referring to Figure 7 of the drawings the numeral 32 designates a blade holder as a whole comprising sections 33 and 34 hinged at one end as shown at 35. The section 33 is provided with knobs or projections 36 corresponding in position to the openings usually provided in safety razor blades and the knobs are adapted to be received in similarly arranged depressions 37 formed in the inner face of the section 34. 10 It will be apparent that a safety razor blade may be arranged between the sections 33 and 34 and held securely in position by the projections 36. The holder 32 when closed is substantially circular in cross-section as shown in Figures 1 and 8 and is adapted to be received in the longitudinal opening 31 of the shaft 27. When the blade is arranged in the holder 32 it projects outwardly through openings 38 formed in the 15 sides of the shaft 27 as clearly shown in Figure 8. The holder 32 when in operative position, projects outwardly beyond the casing as shown in Figure 2 and is provided adjacent its projecting end with an annular 20 groove 39 as shown in Figures 2 and 7. A latch 40 is pivotally connected with one end of the rod 21 and the lower end of the latch is adapted to operate within the groove 39. It will be apparent that the 25 shaft 27 is free to oscillate together with the holder 32 but the latter cannot be withdrawn outwardly from the casing until the latch 40 is released.

As shown in Figures 2 and 3, a spring 41 40 is connected at opposite ends to eyes 42 carried by the disks 24 and 29. The spring 41 is of the tension type and is adapted to cause the shafts 22 and 27 to assume normal positions as shown in Figure 3 at which time the 45 razor blade 43 will be arranged vertically within the casing in alignment with the axes of the shafts 22 and 27. When the blade is in the position shown, the lower rod 20 and the rod 21 will be arranged adjacent and 50 parallel to the edges of the blade for a purpose to be described.

As shown in Figure 1 the numeral 44 designates a strop of the usual type employed for stropping razor blades. The strop is 55 mounted within the casing and is passed about the shaft 22 as clearly shown. It will be apparent that movement of the strop in either direction will cause the shaft 22 to oscillate. A hanger 45 preferably formed of 60 leather or similar material is secured to the upper rod 20 and may be provided in its upper end with an opening (not shown) adapted to receive a hook or other suitable 65 means of support when the device is to be operated.

The operation of the device is as follows:

A blade of the usual type is inserted into the holder 32 and the latter is in turn inserted within the opening 31. The outer portions of the blade will pass through the 70 openings 19 in the casing as will be obvious. When the holder is inserted to the position shown the latch 40 is dropped to engage its lower end within the groove 39 to prevent longitudinal displacement of the holder. 75 The device is then ready for operation and is suitably supported by means of the member 45. The operator grasps the ends of the strop 44, pulling upon one end and permitting the other to move upwardly into the 80 casing. This action starts rotation of the shaft 22 which action is imparted to the shaft 27 through the link 26 until further movement is limited by the sides of the blade coming into contact with the inner surfaces 85 of the strop. Continued movement of the strop will not rotate the shaft 22 but the strop will slip over the shaft until the limit of its movement is reached. The action of the strop is then reversed, the first named 90 end being permitted to move upwardly into the casing while the other end is withdrawn. Just before this action is started, the spring 41 will tend to move the shafts 22 and 27 toward their normal positions thus immediately breaking the contact between the blade and the stropping surfaces to prevent the strop from being cut. It will be apparent 95 that the action just referred to will cause the sides of the blade edges to firmly engage 100 the stropping surfaces of the strop. The arrangement of the lower rod 20 and the rod 21 prevents accidental contact between the edge of the blade and the strop when the stropping action is not being performed. 105 When the stropping has been completed the latch 40 may be raised and the holder 32 withdrawn from the shaft 27, the outer portions of the blade again passing through the 110 openings 19 in the casing.

It is to be understood that the form of my invention herewith shown and described is to be taken as a preferred example of the same and that various changes in the shape, size, and arrangement of parts may be resorted to without departing from the spirit of the invention or the scope of the subjoined claim.

Having described my invention, I claim:

A device of the character described comprising a casing, upper and lower parallel shafts journaled at their ends in said casing, said lower shaft being provided with an axial opening and a pair of diametrically opposite slots communicating therewith, a 120 razor blade holder comprising a pair of sections adapted to be arranged against opposite sides of a blade, the axial opening in said lower shaft being adapted to slidably receive said holder with the outer portions 125 130

of the blade projecting through said slots, said holder being provided with a portion of circular cross section projecting outwardly beyond said casing and provided 5 with an annular groove, the ends of the holder sections projecting beyond the casing being pivotally connected to each other adjacent said groove, a latch pivoted at one end to said casing and having its opposite

end normally arranged in said groove, a 10 strap passed about said upper shaft and having its sides arranged parallel on opposite sides of said lower opening, and connections between said shafts for oscillating them simultaneously in opposite directions when 15 said strap is operated.

In testimony whereof I affix my signature.
VERNON L. CAPWELL.
